UNITED STATES PATENT OFFICE.

GIDEON FLAKE, OF CENTRE VALLEY, INDIANA, ASSIGNOR TO THOMAS I. RUSHTON, OF SAME PLACE.

GATE.

SPECIFICATION forming part of Letters Patent No. 402,578, dated May 7, 1889.

Application filed January 26, 1889. Serial No. 297,611. (No model.)

To all whom it may concern:

Be it known that I, GIDEON FLAKE, a citizen of the United States, residing at Centre Valley, in the county of Hendricks and State 5 of Indiana, have invented new and useful Improvements in Gates, of which the following is a specification.

My invention relates to improvements in gates; and it consists in certain novel features, that will be hereinafter described and claimed.

In the drawings, Figure 1 is a perspective view showing the gate lowered or closed. Fig. 2 is a front elevation showing it raised 15 or open. Fig. 3 is a vertical section on the line $\alpha\alpha$ of Fig. 1, looking in the direction indicated by the arrow. Fig. 4 is a detail view of the catch.

Referring to the drawings by letter, A A 20 designate two posts, which are set in the ground on opposite sides of the roadway, and are connected at their upper ends by the cross bars or beams B B, the said cross bars or beams having longitudinal slots C, in which 25 are mounted pulleys D, for a purpose herein-after set forth.

E E' designate upwardly-converging standards or supports, which are secured to the upper ends of the posts A A, and have their 30 upper ends meeting and secured together at a point vertically over the center of the gate. A frame, F, is supported by the standards E', and consists of the vertical bars G, erected on the said standards, and the horizontal 35 plate or bar H, secured to the said standards and the vertical bars G.

I designates the gate, which is composed of the usual rails, J, and the vertical bars or braces K, connecting the same. The central 40 vertical bar, K, of the gate is extended upward above the upper rail of the gate, and a T-casting, L, is secured to the upper end of said vertical bar. From the center of this T-casting a cable, M, extends upward to and 45 over a pulley, N, journaled in and between the upper ends of the standards E E', and thence outward and over a pulley, O, journaled in the outer end of the horizontal bar or plate H, and thence downward, its free end 50 being provided with a weight, P, which is heavier than the gate, so as to overbalance

the same, and thereby raise the gate when the latch is released, as will be presently more fully described.

The T-casting can be dispensed with by 55 securing the ends of all the cables directly to the gate, as will be readily understood; or the pulleys N O may be provided with grooved peripheries and the operating-tables extended over said pulleys and secured to the weight. 60 These changes are so obvious as to require no illustration, and will readily suggest themselves to the skilled artisan.

To the upper end of the post A, and on that side of the roadway opposite the side at 65 which the weight P is arranged, I secure the longitudinal beam Q, at the ends of which I secure the vertically-arranged pulleys R, as shown.

At the upper ends of the post A, adjacent 70 to the bar Q, I arrange the horizontal pulleys S, and cables T, having weighted handles U, pass over these pulleys R and S, and thence under and around the pulleys D, and are secured to the ends of the T-casting L. 75

The vertical end bars of the gate move in vertical grooves V in the inner opposing faces of the posts A, and the latch or locking device is arranged within the groove in the post at that side of the roadway on which the operating cords or cables T are arranged. In the side walls of the groove in the said post I form the recesses W, in which I pivotally secure the gravity latches or detents Y, each consisting of a shank, Z, pivoted within the post, 85 and a transverse head or locking-pin, a, at the upper end of the shank, which is adapted, when not arranged to lock the gate, to lie within the recess W, but tends to fall away from the said recess by reason of its own gravity. 90 The detents are forced into the said recesses by a vertically-sliding plate, b, which is arranged in the groove V of the post, and is provided in its side edges with the upwardly and inwardly inclined surfaces c, which bear 95 against the locking-pins, so that when the said plate is drawn upward it acts as a wedge on the said pins, so as to force them into the recesses W, and thereby disengage them from the gate. The said plate b is further provided in its edges with the shoulders d, which are adapted to come in contact with the pins, 100

and thereby limit the descent of the said plate, so as to prevent its falling so far as to pass its operative position. The said plate is raised by means of the operating cords or cables *e*, which are secured to the upper end of the said plate and pass upward therefrom over pulleys *f*, secured within the posts, and thence outward to a point near the free ends of the cables *T*.

The end bar of the gate is provided in its opposite edges with the notches *g*, the lower ends of which present the abrupt horizontal shoulders *h*, which are engaged by the locking-pins when the gate is lowered, and the lower end of the said end bar is tapered, as shown at *i*, so that as the gate is lowered the said end bar can enter between the locking-pins and force them apart.

In operation, when it is desired to open the gate, it is only necessary to disengage the locking-pins from the notches, when the weight *P*, being heavy enough to overbalance the gate, will at once draw the same upward, as will be readily understood, and as shown in Fig. 2. When it is desired to close the gate, the cables *T* are drawn upon, so as to pull the gate downward, when the end bar of the gate will pass between the locking-pins, and the said pins will automatically engage the notches *g*. The locking-pins are disengaged from the gate by raising the disengaging-plate *b*, so that the inclined or wedge surfaces of the same will ride against the said pins and force them into the recesses *W* out of engagement with the notches *g*, so that the gate will be free to be acted upon by the lifting-weight *P*.

From the foregoing description, taken in connection with the accompanying drawings, it will be seen that I have provided a very simple and easily-operated gate, which is not liable to get out of order or be otherwise injured.

The locking devices are all inclosed so as to be protected from injury.

My device is designed more especially for use as a farm-gate; but it is equally well adapted for use as a water-gate, and can be used to advantage as a barn-door. The device requires no exertion on the part of the operator, as the gate will be raised by a weight but slightly heavier than itself, and consequently will be opened automatically, while in closing the gate the operator has only to overcome the difference between the weight of the gate and the lifting-weight.

When the gate is locked, it cannot be raised by stock prying under it, but only be raised by releasing the detents. This locking mechanism I regard as the main feature of my invention, and it can be applied to windows without involving any departure therefrom.

Having thus described my invention, I claim—

1. The combination, with the gate-post and the gate having notches in the opposite sides of its end bar, of the inwardly-swinging detents pivoted within the posts and having locking-pins at their upper ends engaging the notches in the end bar of the gate, as set forth.

2. The combination, with the gate-post, of the detents pivoted therein and having locking-pins at their inner ends, and the gate having the lower end of its end bar tapered, and having notches in the opposite sides of the end bar, as and for the purposes set forth.

3. The combination, with the post and the gate, of the detent pivoted in the post and adapted to engage the gate, the disengaging-plate having inclined surfaces bearing against the detent, and mechanism for raising said disengaging-plate, as set forth.

4. The combination, with the post, of the gate moving vertically between the posts and having notches in the opposite sides of its end bar, a lifting-weight connected to the gate to raise the same, mechanism for lowering the gate, and the latches arranged within the posts and engaging the notches in the end bar of the gate to hold it lowered, as set forth.

5. The combination, with the gate-post; the latch arranged within one of the posts and adapted to hold the gate lowered, the converging standards *E*, secured thereon, the frame *F*, erected on said standards, the pulleys in said frame, the gate moving between the posts, the *T*-casting at the upper end of the gate, the cable secured to said casting and extending over the pulleys in the frame *F*, and provided with a weight, the bar *Q*, the pulleys *R* at the ends of the same, the pulleys *S* at the upper ends of the gate-posts, and the cable passing over said pulleys and secured to the ends of the *T*-casting, as specified.

In testimony that I claim the foregoing as my own I have hereto affixed my signature in presence of two witnesses.

GIDEON FLAKE.
